UNITED STATES PATENT OFFICE

172,017

FUEL INJECTION PUMP CALIBRATING STAND

Stanley E. Franklin, Wilmington, Calif., assignor
to Marine Pumps, Inc., Wilmington, Calif., a
corporation of California

Application March 5, 1953, Serial No. 23,920

Term of patent 14 years

(Cl. D52—1)

To all whom it may concern:

Be it known that I, Stanley E. Franklin, a citizen of the United States, and resident of Wilmington in the county of Los Angeles and State of California, have invented a new, original, and ornamental Design for Fuel Injection Pump Calibrating Stand, of which the following is a specification, reference being had to the accompanying drawings, forming part thereof.

Fig. 1 is a perspective view of a fuel injection pump calibrating stand embodying my new design; and

Fig. 2 is a perspective view thereof from the opposite side.

I claim:

The ornamental design for a fuel injection pump calibrating stand, substantially as shown.
